UNITED STATES PATENT OFFICE.

CARL S. SHILLING AND DUFFEY B. LOUZON, OF CHICAGO, ILLINOIS.

DOOR LATCH.

Application filed June 4, 1925. Serial No. 34,766.

Our invention relates to improvements in securing devices for doors and has particular reference to a combined door latch and securing means therefor.

5 One object of the invention is to provide a new and improved combination securing device for doors comprising a latch mechanism and a plurality of differently actuated means for locking said mechanism in latched position.

10 Another object is to provide a novel securing means for a door latch associated with the latch keeper.

15 A further object of the invention is to provide a door latch of simple and inexpensive construction including a pair of latch bars pivoted on the door and a novel means for projecting a securing member into the space between said bars to secure them 20 against disengagement with the latch keeper when the door is in closed position.

25 Further objects and advantages will be apparent from the following detailed description taken in connection with the accompanying drawings in which:

Figure 1 is a rear elevational view of a door latch and two securing mechanisms therefor embodying the features of our invention.

30 Fig. 2 is a sectional view taken along the line 2—2 of Figure 1.

Fig. 3 is a sectional view taken along the line 3—3 of Figure 1 and showing the latch attached to a door.

35 Fig. 4 is a sectional view taken along the line 4—4 of Figure 1 and showing one securing means for the latch mechanism.

40 Fig. 5 is a fragmentary section taken along the line 5—5 of Figure 1 showing another securing means for the latch mechanism.

Fig. 6 is a fragmentary sectional view along the line 6—6 of Figure 1.

Fig. 7 is a front elevation of the latch keeper and a portion of the latch mechanism shown in Figure 1.

45 Fig. 8 is a side elevation of the keeper attached to a door frame.

Figs. 9 and 10 are sections taken approximately along the line 9—9 of Fig. 8 showing parts of a third securing mechanism for the latch in unlatched and latched positions respectively.

50 Figs. 11 and 12 show certain parts of the latch.

55 While we have shown in the drawings and will herein describe in detail the preferred

embodiment of the invention, it is contemplated that various changes in construction and arrangement may be made by those skilled in the art without departing from the spirit and scope of the invention as expressed in the appended claims.

Referring to the exemplary embodiment of the invention illustrated in the drawings, 13 generally designates a latch mechanism 65 mounted in a suitable casing 14 comprising a front wall 15 and side walls 16. The casing may be secured to or mortised in a swinging door 17 in any suitable manner. In the present instance, it abuts against a 70 plate 17^a on the inner side of the door and is held in position by screws 18 entered through holes 19 in the front wall of the casing.

The latch mechanism 13 best shown in 75 Figure 1 comprises a pair of latch bars 20 having overlapping inner ends which are pivotally supported by any suitable means, such as a pin 21 mounted in the casing. The outer ends of the latch bars extend through 80 a slot 21^a in the end of the casing and project beyond the edge of the door. A stiff spring 22 coiled about the pin 21 and having its ends held in notches 22^a in the bars 20 tends to yieldingly press the bars apart. 85

Mounted on the door frame 23 in position to engage the outer ends of the latch bars when the door is closed is a keeper 24 comprising a flat plate 25 having two forward projections 26. The keeper may be suitably 90 secured to the door frame by screws 27 extending through holes 27^a in the plate 25. At their forward ends the projections 26 are formed with opposed cam surfaces 28 which converge rearwardly and terminate at the 95 keeper opening 29. Thus, as the door is closed, the outer ends of the bars 20 will be compressed together by the surfaces 28 and thereby guided into the opening 29. To permit the bars to spring apart after passing 100 the opening 29, the projections 26 are formed with opposed recesses 30 providing shoulders 31 behind which the bars 20 catch and become latched when the door reaches its closed position (Fig. 7).

To unlatch the door and permit it to be opened from either the outside or the inside, a cam member 32 is arranged to release the latch mechanism from the keeper. In the present instance, the cam member 32 consists of an elongated bar having its medial portion journaled in the casing at 33 (Fig. 105

6) and its ends 34 bent at right angles to the body portion so as to overlap the outer edges of the latch bars 20. From Figure 1 it will be seen that as the cam member is rotated in either direction, the angular ends 34 will engage the bars 20 and move them toward each other thereby disengaging the outer ends of the latch bars from the keeper shoulders 31. Rotation of the cam 32 may be effected manually by means of a door spindle 35 extending through a square hole 36 in the cam member and provided at either of its ends with a door knob 37.

Three separate means operable from the inside of the door are provided for securing the latch mechanism in latched position. One of these means shown particularly in Figs. 7 to 10 is associated with the keeper 26 and comprises a lever 38 formed with a wedge-shaped end 39 which may be swung into the space between the outer ends of the bars 20 when the door is in closed position. The lever 38 is fulcrumed intermediate its ends on a pin 40 extending between two lugs 41 on the plate 25. To swing the wedge-shaped end 39 into and out of securing position, the opposite end of the lever 38 is pivotally connected by a pin 40^a to a push rod 42 projecting slidably through a plate 43 on the keeper. A head 44 provides a convenient means for operating the push rod. When the head is pushed inwardly, the end 39 of the lever will be moved into the position shown in Fig. 10 and will prevent the latch bars from being swung together by rotation of the cam 32. The bars may be unlatched by pulling the head 44 outwardly into the position shown in Fig. 9.

Another means for securing the latch mechanism in latched position comprises a block 45 positioned between the bars 20 and the inner side of the front casing wall. The block is adapted to be moved perpendicular to the bars 20. To this end, the block is mounted on a screw 46 extending through an opening 47 in the casing and having a knurled knob 48 on its outer end. 49 is a clip encircling the screw 46 between a shoulder 50 and the inner side of the casing wall to hold the screw against outward movement. To limit the movement of the block toward the bars and to prevent rotation of the block 45 when the screw is turned, lateral arms 51 are formed on the block in position to engage lugs 52 on the inner side of the casing wall 15. Rectangular notches 52^a preferably are formed in the latch bars 20 to receive the upper and lower edges of the block. Assuming the latch mechanism to be in latched position, rotation of the knob 48 in one direction through several revolutions will cause the block 45 to move along the screw into the space between the latch bars (Fig. 5) thereby securing them apart. To unlatch the bars, the knob is rotated

through the same number of revolutions in the opposite direction.

As a third means for securing the latch bars 20 apart and preventing their disengagement with the keeper 24, an upright lever 53 is mounted between the bars and the door so that its upper end may be moved toward and away from the bars. The lever 53 is fulcrumed on a bolt 54 which connects a lateral arm 55 on the lever with a lug 56 integrally formed on the inner side of the casing wall 15. At its upper end the lever 53 has a short lateral projection 57 which is adapted to enter a space between the bars 20 formed by two opposed notches 58. To swing the lever on its pivot pin, a cam member 59 having an inclined circular cam surface 60 is journaled in an opening 61 in the casing and is provided with a knurled knob 63. The lower end of the lever 53 has an angular projection 64 which is yieldingly held against the cam surface 60 by a spring 65 coiled about the pivot bolt 54. One end of the spring bears against the front wall 15, and the other end is held against a lateral arm 66 on the lever 53. Assuming the latch mechanism to be in unlatched position (Fig. 3), rotation of the knob 63 through one half of a revolution will cause the lever 53 to be moved into the position shown in Fig. 4 thereby bringing the projection 56 between the latch bars. Unlatching of the latch mechanism is effected by the spring 65 as the cam is rotated in the opposite direction.

If desired, suitable tumbler levers may be associated with the actuating devices for the latch securing means within the casing 14 so that the door may be unlatched from the outside in the usual way.

From the foregoing it will be seen that three independent mechanisms have been provided each being adapted to project a separate securing member transversely of the latch bars and into the space between them. In one of the mechanisms the securing member is actuated by reciprocating the push rod 42, in another by rotating the knob 48 through several revolutions, and in a third by rotating the knob 63 through one half of a revolution. The three mechanisms are thus differently actuated and constitute a combination latch which will prevent strangers from easily or quickly unlatching the door to which the latch is applied. Each of the securing mechanisms by itself will effectively secure the latching mechanism and prevent the door from being opened from the outside.

We claim as our invention:

1. A securing device comprising, in combination with a door and a door frame, a latch mechanism including a pair of bars pivotally mounted on the door and having ends projecting beyond one edge thereof, a

keeper mounted on the door frame and having an opening to receive said ends as the door is closed, resilient means for separating said bars within the keeper, a lever fulcrumed intermediate its ends on said keeper, and means connected to one end of said lever for swinging the opposite end between the ends of said bars to secure them in the keeper.

10 2. A securing device comprising, in combination, a keeper adapted to be mounted on a door frame, a latch mechanism including a pair of bars adapted to be pivotally mounted on a door in position to engage said keeper as the door is closed, and a securing member pivotally mounted on said keeper and adapted to be swung into engagement with said bars to secure them in the keeper.

15 3. A securing device comprising, in combination with a door and a door frame, a latch mechanism comprising a pair of bars pivotally mounted on the door, and means yieldingly holding said bars apart, a keeper positioned on the door frame to receive said bars in latching engagement as the door is closed, and a member on the door movable into and out of the space between said bars to secure said mechanism in latched position.

20 4. A securing device comprising, in combination with a swinging door and a door frame, a pair of latch bars pivotally mounted on the door, a keeper mounted on the door frame to engage said bars as the door is swung into closed position, a member adapted to be manually projected into the space between said bars to secure them in latched position, and means for moving said member.

25 5. A securing device comprising, in combination with a hinged door and a door frame, a pair of latch bars pivotally mounted on the door, a keeper mounted on the door frame to engage said bars as the door is swung into closed position, a member adapted to be moved transversely of and into the space between said bars to secure them in latched position, and screw means for moving said member.

30 6. A securing device comprising, in combination with a hinged door and a door frame, a pair of latch bars pivotally mounted on the door, a keeper mounted on the door frame to engage said bars as the door is swung into closed position, a member adapted to be moved transversely of and into the space between the bars to secure them in latched position, and reciprocatory means for moving said member.

35 7. A securing device comprising, in combination with a door and a door frame, a pair of latch bars pivotally mounted on the door, a keeper mounted on the door

frame to engage said bars as the door is moved into closed position, a member adapted to be moved transversely of and into the space between the bars to secure them in latched position, and cam actuated means for moving said member.

70

8. A securing device having, in combination with a door and a door frame, a casing adapted to be secured to a door, a pair of bars having their inner ends pivoted on said casing and their outer ends projecting beyond the edge of said door, a keeper adapted to be mounted on a door frame in position to receive said outer ends in latching engagement as the door is moved into closed position, a lever pivoted on said casing, and means for projecting one end of said lever into the space between said bars to secure them in the keeper.

75

9. A securing device having, in combination, a casing adapted to be secured to a door, a pair of bars having their inner ends pivoted on the casing and their outer ends projecting beyond the edge of said door, a keeper adapted to be mounted on a door frame in position to receive said outer ends in latching engagement as the door is moved into closed position, a screw mounted on the casing and operable from the inner side of the door, and a block mounted on said screw and adapted to be moved into the space between said bars by rotation of the screw whereby to secure the bars in latched position.

80

90

95

10. A combination door latch comprising, in combination, a latch mechanism adapted to be mounted on a door, said mechanism including a pair of bars arranged for pivotal movement toward and away from each other, a keeper adapted to be mounted on a door frame in position to engage said mechanism when the door is closed, a plurality of means each adapted to be moved into position between the bars of said latch mechanism for securing said mechanism in latched position, and differently operable means for actuating each of said securing means.

100

11. A securing device comprising, in combination with a door and a door frame, a latch mechanism on the door, said mechanism including a pair of bars arranged for reciprocal movement toward each other, a keeper on the door frame adapted to engage said mechanism when the door is closed, and a plurality of independent and differently operable means on said door and said keeper said means being movable into the space between said bars for securing said mechanism in the keeper.
